NAPKIN DISPENSER

Samuel N. Hope, Jr., Wauwatosa, Wis., assignor to Griffith-Hope Company, Milwaukee, Wis.

Filed Aug. 14, 1972, Ser. No. 280,440

Term of patent 14 years

Int. Cl. D7—99

U.S. Cl. D7—72

Fig. 1

Fig. 2

Fig. 3

FIG. 1 is a front elevational view of a napkin dispenser showing my new design; the rear being identical thereto;

FIG. 2 is a top plan view thereof;

FIG. 3 is a right side elevational view thereof, the left side being identical thereto.

I claim:

The ornamental design for a napkin dispenser, substantially as shown and described.
